UNITED STATES PATENT OFFICE

147,136

DESIGN FOR A DETERGENT SUPPLY TANK
FOR DISHWASHING APPARATUSEugene M. Morehouse, Tujunga, Calif., assignor
to Adel Precision Products Corp., a corporation
of California

Application February 20, 1946, Serial No. 126,725

Term of patent 3½ years

(Cl. D4—2)

To all whom it may concern:

Be it known that I, Eugene M. Morehouse, a citizen of the United States and residing at Tujunga, in the county of Los Angeles and State of California, have invented a new, original, and ornamental Design for Detergent Supply Tank for Dishwashing Apparatus, of which the following is a specification, reference being had to the accompanying drawing, forming part thereof, in which:

Fig. 1 is a front elevation showing my new design of a detergent supply tank for dishwashing apparatus;

Fig. 2 is a top plan view with the spout shown broken away for convenience of illustration;

Fig. 3 is a rear elevation; and

Fig. 4 is an end elevation as viewed from the left hand end of Fig. 1.

I claim:

The ornamental design for a detergent supply tank for dishwashing apparatus, substantially as shown.

EUGENE M. MOREHOUSE.
